UNITED STATES PATENT OFFICE

2,442,570

HOLDER

Frank H. Post, Ashtabula, Ohio

Application September 9, 1946, Serial No. 695,739

1 Claim. (Cl. 242—130)

1

This invention relates to new and useful improvements and structural refinements in holders, and the principal object of the invention is to provide a device of the character herein described, such as may be conveniently and effectively employed for holding a ball, a spool, or a skein of yarn or other material, so as to permit the same to be easily unwound and fed to a machine or into the hand of the user for subsequent fabrication.

A further object of the invention is to provide a holder which may be readily attached to and detached from its supporting structure, such as the arm of a chair, the top of a desk or table, and the like.

Another object of the invention is to provide a holder which is of a collapsible character, so that when it is not in use, it may be easily stored or carried in a hand bag, or upon the person of the user.

An additional object of the invention is to provide a holder which is simple in construction, which will not easily become damaged, which will readily lend itself to economical manufacture, and which is otherwise well adapted for the purpose for which it is invented.

With the above more important objects in view, and such other objects as may become apparent as this specification proceeds, the invention consists essentially of the arrangement and construction of parts as illustrated in the accompanying drawings, in which:

Figure 1 is a side elevation of the invention;

Figure 2 is an end view thereof, taken in the direction of the arrow 2 in Figure 1;

Figure 3 is a top plan view showing the same in the collapsed position;

Figure 4 is a cross-sectional view, taken substantially in the plane of the line 4—4 in Figure 3; and

Figure 5 is an end view taken in the direction of the arrow 5 in Figure 1.

Like characters of reference are used to designate like parts in the specification and throughout the several views.

Referring now to the accompanying drawings in detail, the invention consists of a holder designated generally by the reference character 10, the same being formed from any suitable material and embodying in its construction a pair of juxtaposed arms 11 and 12, configurated substantially as shown.

It will be noted that the arm 11 is provided medially of its length with a protuberance 13, while the arm 12 is formed medially of its length

with a recess 14 which is complementary to and provides a seat for the protuberance.

The arms 11 and 12 form at one end thereof a pair of clamping jaws 15 and 16 respectively, while the remaining end portions of the arms provide a pair of finger-pieces 17.

The adjacent surfaces of the arms 11, 12 are also formed with suitable recesses 18 to accommodate the end portions of a tension spring 19 which is secured to the arms by means of transversely extending pins 20.

The arm 11 is also formed with a relatively thick portion 21, in order that it may be provided with a longitudinally extending slot or groove 22, configurated substantially as shown. One end of a pin 23 is pivotally mounted in the slot 22 by means of a transversely extending shaft 24, as will be clearly apparent from the accompanying drawings. The remaining end portion 20 of the pin 23 is of a substantially reduced diameter, as indicated at 25.

It will be noted that the protuberance 13 and the seat 14, in effect, assume the form of juxtaposed frusto-conical sections, as is best illustrated in the accompanying Figure 3. By virtue thereof, the arms 11 and 12 will be prevented from becoming laterally displaced with respect one to the other, while at the same time, the engagement of the protuberance with the seat will 30 be of a fulcrum-like nature, as will be clearly apparent.

The function of the spring 19 is not only to urge the jaws 15 and 16 together, but also to connect the arms 11 and 12 by maintaining the 35 protuberance 13 in engagement with the seat 15.

When the invention is placed in use, the jaws 15, 16 may be spread apart by simply compressing the fingerpieces 17 as indicated by the phantom line 12', whereby the holder may be readily attached to the arm of a chair, the top of a table, or the like. The pin 23 is normally in the upright position, so to speak, as illustrated in the accompanying Figure 1, and a ball, a spool, or a skein of yarn or other material may be positioned 40 on the pin, as is indicated by the phantom line 26. The ball 26 is, of course, freely rotatable on the pin, whereby the pin will constitute what may be referred to as a spindle, from which the material forming the ball may be readily unwound and fed to the machine or into the hand 45 of the user for subsequent fabrication.

When the invention is not in use, the pin 23 may be collapsed or folded, so to speak, in the direction of the arrow 27, so as to lie flat against 50 the outer surface of the arm 11, with a portion

thereof being disposed in the slot 22, as will be clearly understood. In this position, the holder may be easily stored or transported upon the person of the user.

It is believed that the advantages and use of the invention will be clearly apparent from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope 15 of the invention as claimed.

What I claim as my invention is:

A holder comprising a pair of juxtaposed arms forming finger pieces and coacting clamping jaws, a spring urging said jaws together, one of said

arms being formed in its outer surface with a longitudinally extending groove, and a collapsible spindle pivoted at one end thereof in one end portion of said groove, said groove receiving said spindle in its collapsed position.
